(57) **CLAIM**

The ornamental design for a medical patch, as shown and described.

DESCRIPTION

FIG. 1 is a perspective view of a medical patch showing our new design;

FIG. 2 is another perspective view of the medical patch of FIG. 1;

FIG. 3 is a rear elevational view of the medical patch of FIG. 1;

FIG. 4 is a front elevational view of the medical patch of FIG. 1;

FIG. 5 is a left side elevational view of the medical patch of FIG. 1;

FIG. 6 is a right side elevational view of the medical patch of FIG. 1;

FIG. 7 is a top plan view of the medical patch of FIG. 1; and, FIG. 8 is a bottom plan view of the medical patch of FIG. 1.

The broken lines shown in the drawings illustrate portions of the medical patch that form no part of the claimed design.

1 Claim, 5 Drawing Sheets
